UNITED STATES PATENT OFFICE.

JAMES C. MEEM, OF BROOKLYN, NEW YORK, ASSIGNOR OF ONE-HALF TO FREDERICK L. CRANFORD, OF BROOKLYN, NEW YORK.

TUNNEL-LINING.

1,350,556.

Specification of Letters Patent. Patented Aug. 24, 1920.

Application filed April 24, 1919. Serial No. 292,306.

To all whom it may concern:

Be it known that I, JAMES C. MEEM, a citizen of the United States, residing at Brooklyn, in the county of Kings and State 5 of New York, have invented certain new and useful Improvements in Tunnel-Linings, of which the following is a specification.

The principal object of my invention is 10 to provide a new and improved structure for the lining of tunnels. My improved tunnel lining is especially adapted for large tunnels in soft earth formations as distinguished from self-supporting rock. It finds 15 an important application in walling up tunnels that are built by the shield and compressed air method. In one aspect my invention involves building a lining of two series of units, one of metal and the other 20 of concrete, the two series being securely united together. All these objects and advantages of my invention will be made apparent in the following specification taken with the accompanying drawings, in which 25 I have shown one specific embodiment. It is this embodiment which is described in the following specification. It will be understood that modifications may be made within the scope of the invention.

Referring to the drawings, Figure 1 is a 30 diagrammatic axial section of the tunnel in partially completed condition.

Fig. 2 is a cross section of the same principally on the line 2—2 of Fig. 1.

Fig. 3 is an enlarged transverse section 35 showing details of the tunnel lining on the line 3—3 of Fig. 4, before grout is filled in, and

Fig. 4 is a development of a section made 40 by cylindrical surfaces at different radii for different blocks, and looking in the direction of the arrows 4, 4 in Fig. 3.

For the sake of clearness, many details 45 that occur repeatedly in the actual structure, are not repeated throughout the drawings.

The tunnel with the side walls 11 and un-excavated front face 12 has the shield 13 across its front end. This shield has a hood 14 with a cutting edge, a tail 15 and a door 50 opening 9 through which the excavated material may be passed. It will be understood that across the tunnel somewhere in the rear

there is a bulkhead with an air-lock, and the space in front of this bulkhead is filled with compressed air. Jacks are employed 55 between the shield and the tunnel lining to advance the shield. One such jack is indicated at 7, but for the sake of clearness, the others are not shown. The inner side of the shield 15 has longitudinal ribs 16 to 60 strengthen it and to serve as guides around the outside of the tunnel lining. Wads 17 of clay or other suitable material are packed back behind the tail 15, being passed between the guides 16 by suitable compara- 65 tively small jacks, according to the invention covered by my Patent Number 1,246,134, granted Nov. 13, 1917.

The outer metal blocks are indicated generally by the reference number 18 and the 70 inner concrete blocks by the reference number 19. Each outer block 18 consists of a rectangular steel plate 20 bent to suitable curvature with two channel bars 8 having a flange of each riveted or welded across a re- 75 spective end of the plate. At equal intervals three intermediate I-beams 21 have their flanges on one side riveted across the plate 20. Short lengths of channel bar 22 are then riveted along the side edges of the 80 plate 20, being cut to fit in between the cross channels 8 and cross I-beams 21 are also riveted to the plate 20. Thus it will be seen that each metal block 18 consists of a curved outer plate 20 with the channels 8 and 22 85 and I-beams 21 and 23 disposed to form an array of pockets or cells 24 opening on the concave side of the block, that is, toward the axis of the tunnel.

The blocks 18 of one course are fastened to 90 the similar blocks of the preceding course by means of bolts 25 through the marginal channels 22. The adjacent blocks 18 of the same course are fastened together by bolts 26 through the webs of the adjacent end 95 channels 8.

The concrete blocks 19 are made in molds with suitable reinforcing members 27 embedded therein. Each concrete block 19 has a series of radial pipes 28 extending through 100 it. These pipes are for introducing grout after assembly, the inner end of each pipe 28 being screw-threaded at 30 and surrounded by a small open pocket 29 to facili-

tate the attachment of a pipe coupling for supplying the grout.

Embedded in each concrete block 19 is a series of heavy parallel cast iron pipes 31, which serve as columns to sustain the thrust of the jacks 8 in advancing the shield. The adjacent ends of the concrete blocks 19 in the same course are channeled to receive similar thrust columns 31.

10 The blocks 19 are formed with the projecting looped bars 32 as shown in Fig. 3.

The successive courses of the metal blocks 18 break joints and likewise the successive courses of the concrete blocks break joints; 15 also the joints between courses for the concrete blocks are off-set a quarter of a block width compared with the corresponding joints for the metal blocks. This quarter width off-set is indicated by the reference number 33 on Fig. 4. The arrangement is such that two grout pipes 28 open into each pocket 24 of the steel blocks 18 and two members 32 project into each pocket 24.

The metal blocks 18 are assembled, a 25 course at a time, at a convenient distance behind the shield 13 and within the tail 16. Each added course is bolted securely to the preceding course by means of the bolts 25 and the blocks of the course are bolted to 30 each other at 26. A special key block 34 may be employed at the top as shown in Fig. 2. The guides 16 carried by the tail 15 rest on the lining blocks 18 and the clay filling wads 17 are pushed back between the guides 35 16 and between the inner face of the shield 15 and the outer face of the last course of metal blocks 18, as in my patent already referred to. The shield is advanced by jacks such as 7 engaging the concrete blocks 19.

40 Following the placing of a course of metal blocks 18 a course of concrete blocks 19 is placed so that it will extend a quarter block width behind the advance edge of the metal blocks. This quarter block width gives 45 room to reach inside the pockets such as 24 in Fig. 4 to manipulate the bolts 25, when the next course of metal blocks 18 is added. Each course of concrete blocks 19 will require temporary false work to place them over-head until secured by the special key-block 35. At a suitable time after the assembly has been made as described, a pipe will be attached to the threaded pipe end 30 and grout forced into the pocket 24 filling it 50 and extending all around the projecting loop parts of the members 32. As the grout enters the pocket 24 the air can escape through the other pipe 28 associated with the same pocket 24. This grout will extend under the flanges of the channels and I-beams that bound pocket 24 and through and around the loop 32 and thus securely unite the metal and concrete linings together and at the 55 same time seal the tunnel lining as a whole against the entrance of water.

Heretofore it has been common to line tunnels with massive cast iron blocks, but these are very expensive and my improved tunnel lining reduces this expense by employing comparatively light metal blocks in 70 conjunction with massive concrete blocks. The concrete is well adapted to withstand the enormous compressive stresses to which the tunnel lining is subjected and the metal structure is adapted to meet any tensile 75 stresses to which the lining may incidentally be subjected.

I claim:—

1. A tunnel lining comprising an outer wall lining of metal forming a series of inwardly opening cells provided with locking parts, an adjacent inner lining of blocks also provided with locking parts, and means for introducing a binding material into said cells to interlock the locking parts of the 85 cells and blocks together.

2. A tunnel lining comprising an outer wall lining of metal sections and an inner lining of blocks supported thereon, each of said linings having locking portions adapted to receive hydraulic cement in fluid form and to lock the same therein when set, and an intermediate binder interlocking the said locking portions and comprising hydraulic cement introduced to said locking portions 95 in fluid form and then allowed to set.

3. A tunnel lining comprising an outer wall lining having a series of metal sections each section having a plurality of inwardly projecting portions forming inwardly directed cells with locking parts therein, an adjacent inner lining of blocks adapted to rest against the inner edges of said cells and having locking parts therein, and a binding material filling the space between said cells 100 and said blocks and binding the locking parts of the two linings together.

4. A tunnel lining comprising an outer wall of metal blocks formed with pockets opening toward the tunnel axis, an inner 110 wall of concrete blocks with members embedded therein and entering said pockets and grout filling said pockets and engaging said members.

5. A tunnel lining comprising an outer 115 wall of metal blocks having pockets therein, an adjacent inner wall of concrete blocks and pipes through the concrete blocks for the introduction of grout for said pockets.

6. A tunnel lining comprising an outer 120 wall of metal blocks having pockets opening toward the tunnel axis, and an adjacent inner wall of concrete blocks having pipes extending radially therethrough for the introduction of grout to said pockets and having members embedded therein and projecting into said pockets to be engaged by the grout.

7. The method of lining a tunnel comprising constructing an outer wall lining of 130

metal sections with cells having locking portions, building thereon an inner lining of blocks adjacent the inner surface of said outer wall and with locking portions complementary to the locking portions of said outer wall, leaving openings to the spaces between the adjacent locking portions of said linings, filling in said spaces surround-

ing the locking portions with a hydraulic cement in fluid form, and allowing the 10 cement to set and form an intermediate hard substance interlocking with the respective locking parts of the said outer and inner linings.

JAMES C. MEEM.
